UNITED STATES PATENT OFFICE.

OTTO PETERMANN, OF GROTON, NEW YORK, ASSIGNOR TO CORONA TYPEWRITER COMPANY, INC., A CORPORATION OF NEW YORK.

TYPE-WRITING MACHINE.

1,232,837.

Specification of Letters Patent. Patented July 10, 1917.

Application filed August 18, 1914, Serial No. 857,344. Renewed December 14, 1916. Serial No. 137,060.

To all whom it may concern:

Be it known that I, OTTO PETERMANN, a citizen of the Republic of Switzerland, and a resident of Groton, county of Tompkins, and State of New York, have invented certain new and useful Improvements in Type-writing Machines, of which the following is a full, clear, and exact description.

This invention relates more particularly to the ribbon vibrator and support and to carriage attachments of visible or front strike typewriting machines.

One of the main objects of the invention is to provide a simple and efficient ribbon holder or vibrator which is vertically movable upon a support forming a type aliner and which is adapted to hold the ribbon at two points located on opposite sides of the printing point, the said ribbon being actuated in such a way as to move the ribbon to and from the printing point or to cause it to remain inactive for stenciling purposes.

Other objects of the invention are to provide a simple type aliner and guide for the ribbon holder; to provide simple means whereby, a line gage and scale or either of them may be employed in connection with the ribbon vibrator and aliner and the parts so constructed that a part of the scale may be readily seen at or below the printing point; and to provide simple means whereby the carriage may be made to register at the printing point.

Another object of the invention is to provide simple and efficient means whereby the scale may be mounted so as to be supported upon the paper apron and in such a way that when the paper apron is released or moved away from the platen, the scale will also be released.

A further object of the invention is to provide a machine in which the vibratory mechanism, scale, pointer, aliner and gage and correlated parts may be mounted to have a vertical shift with the platen and carriage.

A still further object of the invention is to provide mechanism and attachments which are particularly adapted for front strike foldable typewriters in which the carriage and parts are adapted to be moved forward into overhanging relation to a keyboard to make the machine compact and to adapt the same for transportation purposes.

With these and other objects in view, the

invention will be hereinafter more particularly described with reference to the accompanying drawings, which form a part of this specification, and will then be pointed out in the claims at the end of the description.

In the drawings, Figure 1 is a vertical section, partly in elevation, of one form of machine embodying my invention.

Fig. 2 is an enlarged fragmentary front elevation of the aliner, ribbon holder, showing the ribbon holder in its uppermost position.

Fig. 3 is a vertical section, taken on the line III—III of Fig. 2.

Fig. 4 is a transverse section through the machine frame showing the carriage and attachments in front elevation, the line gage being removed.

Fig. 5 is a fragmentary sectional plan taken on the line V—V of Fig. 4, with the line gage in position.

Fig. 6 is a detail plan view of one form of mechanism that may be employed for imparting a vertical movement to the ribbon holder; and

Fig. 7 is a fragmentary front elevation showing an index or pointer formed as a part of the type aliner and guide.

While I have shown the invention as applied more particularly to a typewriter in which the platen and carriage are foldable forward into overhanging relation to the keyboard or otherwise constructed so as to make the machine more compact when not in use, it will be understood that the invention is applicable in whole or in part to machines of various constructions.

The frame 10 may be of any suitable construction and may comprise the sides 11 and a rear plate 12 integral with the side plates. At the rear corners of the machine frame are brackets 13 in which are movably held the guide posts or slides 14. These posts or slides may be connected at their lower ends by a transversely extending rod 15 and this rod may be connected to shift levers 16 and 17 by which the slides may be given vertical shift movement in the usual or in any preferred way. The posts or slides 14 at their upper ends are secured to arms or bars 18. These bars or arms 18 each have an arm 19 pivoted thereto, as at 20. A carriage bed 21 is rigidly held to the arms 19 at their rear portions and said bed with the

arms 19 form one member of a foldable support, the other member comprising the bars 18. A transversely movable carriage 22 is suitably held and guided on the bed 21 and in said carriage is mounted a platen 23. The carriage and platen are adapted to be movable forward with the foldable member of the support into overhanging relation to the keyboard as is usual in this type of machine.

A number of key-levers 24 are pivotally held to a plurality of transversely extending rods 25 forming a keyboard with three sets or banks of keys, not shown, and each key-lever is held in its normal position by a spring 26, one end of which is attached to one of the key-levers and its other end to a transversely extending bar 27. Each key-lever has a part 28 which is connected by a link 29 to a type-bar 30. The type-bar 30 may have the usual number of type and is adapted on the depression of a key-lever to be forced upward and rearward for printing purposes, the said type-bar being pivoted to a hanger 31 or to a segment or other support. The key-levers 24 each have a tongue or projection 32 which is adapted to engage a universal bar 33. This universal bar may be provided with vertically extending integral arms 34, the upper ends of which are pivoted, at 35, to the arms 36 of bell-crank levers 37. There are two bell-crank levers 37 located on opposite sides of the machine and said bell-crank levers are pivoted, at 38, and each have a part 39 adapted to enter a vertical slot 40 in one of the vertically extending arms 41 located at opposite sides of the machine. These arms 41 are mounted upon the transversely extending rod 15 so as to rock thereon and to partake of the shift movement thereof, and at the upper ends said arms are connected by an integral transverse bar 42 forming with the arms a rocking universal bar frame or escapement frame. The bar 42 may be provided with a tappet 43 which is adapted to engage the bendable end 44 of a dog carrier. The dog carrier may have mounted thereon the limber or loose dog 46 and the fixed dog 47, the said dogs co-operating with the teeth of a rack 48 mounted on the base plate 49 of the carriage 22. The carriage 22 is normally forced in a letter-spacing direction by a flexible connection 50 arranged around a spring drum 51 and forming a part of the carriage tension or propelling means. At each side of the machine and on the arms 19 of the foldable support is mounted a ribbon spool 52. These ribbon spools are rotatably held in any desired way and extending between the spools is a ribbon 53 which is adapted to be wound from one spool to another by suitable mechanism, not shown, operatively connected so as to be operated by the universal bar frame when

the key-levers are depressed. The ribbon may have one or a plurality of colors and is adapted to be moved to and from the printing point or may remain inactive to permit stencils to be made. As shown, a bracket 54 is held to the carriage bed 21 and said bracket has an upwardly extending arm 55 to which is pivoted one end of a vibrator arm 56. The vibrator arm, Figs. 4 and 6, has a downwardly extending portion 57 which passes through a guiding slot 58 of the bracket 54 and between the walls 59 and 60 of a pivotally held lever 61. The lever 61 is adjustably mounted upon an actuating member 62. This actuating member is pivoted, at 63 to rock back and forth on the bracket 54 and is normally held against inward rocking movement by a spring 64, one end of which is attached to a lug on the actuating member and the other end to a lug on the bracket 54. The lever 61 is held in any one of three adjusted positions by means of a corrugated integral portion 65 of the member or actuator 62 and has a finger portion 66 by which said lever may be moved. This lever has an opening 67 through which may be seen either one of three letters or characters, these being indicated by the upper case letters, S, B and R, the letter S standing for stenciling, B to indicate the black field of the ribbon, and R the red field of the ribbon, though other colors may be used. The walls 59 and 60 of the lever 61 form cam surfaces so that when the actuating member 62 is moved on its pivot, it will force the part 57 lengthwise of the platen to force the arm 56 both up and down. If the lever 61 is moved to a position over the character S, the walls 59 and 60 are so positioned with respect to the lower end 57 that during the actuation of the member 62, the walls will not move the vibrator arm 56 and therefore the said arm will remain inactive. A projecting portion or finger 68, Fig. 1, enters a slot 69 in the actuating member so that as the arm 41 of the universal bar frame is moved back and forth, it will transmit a rocking movement to the actuating member 62. The connection between the finger 68 and the actuating member 62 is such that the ribbon vibrator mechanism described may be folded forward with the carriage and platen and may be made to engage therewith without any disorganization whatever, when the carriage and platen are restored to their normal working position. The ribbon mechanism described for operating the arm 56 is the same as disclosed in my Patent No. 1,121,044, dated December 15, 1914, and the other parts already referred to may be of the usual or of any preferred construction, many of such parts being covered by other patents or pending applications filed by me.

The carriage bed 21 has a guide and type aliner 70 secured to the under face thereof. This aliner and guide or device may be made from steel or other material and is substantially L-shaped. It has inwardly extending lugs or parts 71 through which pass the screws 72 for securing the same to the carriage bed and has a vertically extending plate-like portion 73. The portion 73 of the aliner or device 70 has an elongated slot 74 at the lower portion thereof and an inverted substantially T-shaped slot 75 at the upper portion, above which slot the ends or parts 76 are bent inward, as at 77, to guide and align the type at the printing point.

10 The device 70 forms a support for a ribbon holder 78. This ribbon holder may be of sheet steel and is of a skeleton form. The ribbon holder which forms a part of the 20 ribbon vibrator has substantially C-shaped parts 79 located on opposite sides of the printing point and have vertical slots 80 which are intersected by smaller angularly arranged slots 81. The ribbon is threaded through the slots 81 and into the vertical slots 80 of the part 79 and extends across the open space between the C-shaped parts 79. The parts 79 of the ribbon holder are separated by a suitable space below said 30 parts 79, a relatively large opening 82 is provided. The ribbon holder is provided with two integral lips or parts 83 which extend inward about the edges 84 of the aliner and guide 70. At the lower end of the 35 ribbon holder is a pendent part 85, the lower end of which is bent upward and is substantially T-shaped, as at 86. The part 86 is passed inward through the slot 74 so as to extend transversely of said slot and together with the lips 83 serve to retain and guide the ribbon holder on the type aliner. The part 85 is of substantially the same width as the slot 84 and the edges 87 of said slot form guides for the lower end of the ribbon 40 holder. The holder is thus positively guided in its vertical and up-and-down movement. A pin or projection is located at the rear of the ribbon holder, the form of pin shown being the body of a screw, and said projection enters a slot 89 in the outer end of the 50 vibrator arm 56. The holder thus forms one part or member of the ribbon vibrator and the arm 56 another part or member, the slot 89 permitting the rocking movement of the arm 56 and the vertical movement of the 55 ribbon holder 78. The lugs 83 are shown in their extreme upper movement as engaging the lower edge of the inturned type guides 77, but no stop, as for example the 60 shoulders of the guides 77, is necessary because the ribbon vibrator is moved positively up and down by the lever 61.

It will thus be evident that when the 65 vibrator mechanism is actuated by the depression of any one of the key-levers, the arm 56 will be rocked and through this rocking action, the vibrator holder will be moved vertically to carry the ribbon to and from the printing point. It will be evident also that by reason of the mounting of the aliner or device 73 on the carriage bed so as to partake of the shift movement of the platen and carriage, there is no relative change between the position of the aliner and the printing point, and further by mounting the aliner 70 on the carriage bed with the ribbon vibrator and ribbon mechanism, they can all partake of the folding movement of the platen and carriage.

70 A line gage 90 may be secured to the aliner and guide or device 70 at the rear thereof and at the rear of the ribbon vibrator. This line gage is provided with a relatively large opening 91 substantially V-shaped at the upper end to provide a correspondingly shaped 80 part 92, the apex of which is directly over the printing point, and has outwardly extending arms 93 on each of which may be a scale 94. The upper edge of the scale is adapted to register with the printing line, 90 and said gage at its lower portion is secured by screws 95 or otherwise to the inner part of the aliner. The upper portion 92 of the gage might be made to extend inward and slightly about the platen so as to press the 95 work sheet against said platen, the said line gage being also adapted to hold small articles, as labels, cards and the like which cannot well be held by the usual paper fingers.

Extending lengthwise of the platen and carriage is a scale 96. This scale 96 is mounted to travel with the carriage and has a scale both at the upper and lower edge thereof. The scale is supported by downwardly extending arms or parts 97 of the paper 100 apron 98, Fig. 3, and has its upper edge located adjacent to the surface of the platen. The scale 96 is adapted to be moved with the paper apron away from the platen when placing the work sheet thereabout, said means not being shown as it may be of any preferred form. It will be noticed that the scale extends across the aliner and ribbon vibrator and the open space formed in the aliner and in the ribbon vibrator holder 78 is such 105 that a part of the scale may be seen through such opening for registering purposes at the printing point, and to assist in such registration, an indicator, as a mark 99, may be employed, or instead of a mark an integral projection forming a pointer or index, as at 100, may be used as shown in Fig. 7, the construction shown in said figure being identically the same as in the other views except as to the integral pointer or index 100. It will be 110 seen, therefore that the scale, pointer, aliner and guide, ribbon vibrator and actuator therefor, all partake of the shifting movement of the platen carriage and also in its folding movement so as to move all the parts 115 120 125 130

from a normal operative printing position away from the type-bars to fold over the keyboard, or if the folding operation is less than those shown, these parts may fold over 5 and above the type-bar basket.

From the foregoing, it will be evident that simple means is provided whereby the ribbon vibrator and holder may be properly guided adjacent to the printing point to move 10 the ribbon so as to cover and uncover the printing point; that the said vibrator parts and aliner as well as the line gage may be stamped from sheet metal, as steel or other material; that effective means is provided 15 whereby the type aliner may properly guide the ribbon holder; and the said means is simple in construction and may be readily assembled.

Having thus described my invention, I 20 claim as new and desire to secure by Letters Patent:—

1. In a typewriting machine in which the type-bars have an upward and rearward movement and in which the carriage and platen may fold to make the machine compact, the combination of a vertically movable carriage bed, a support for said bed, an aliner and guide held in said bed, a ribbon holder movably held on said aliner, a paper 25 apron, and a scale mounted at the forward edge of said apron to travel with the carriage, said aliner and ribbon holder being open to permit a part of the scale to be seen.

2. In a typewriting machine in which the type-bars have an upward and rearward movement and in which the carriage and platen may fold forward to make the machine compact, the combination of a vertically movable carriage bed, a support for 30 said bed, an aliner held to said bed, a ribbon holder movably held on said aliner, a paper apron having pendent arms at the forward edge thereof, and a scale mounted on said arms to travel with the carriage.

3. In a typewriting machine, the combination of a support, a carriage adapted to travel along said support, a device and guide mounted on the support, a ribbon holder having parts located on opposite sides of the 35 printing point and with a pendent portion engaging a part of the device so as to be guided thereon, and means for imparting a vertical movement to said ribbon holder.

4. In a typewriting machine, the combination of a support having an up-and-down movement, a substantially L-shaped sheet metal aliner and guide secured to said support and having a vertical slot at the lower portion thereof and a substantially T-shaped slot at the upper portion with an integral inturned type guide at the upper part thereof, a ribbon holder having substantially C-shaped and vertically arranged ribbon holding portions on opposite sides of the 45 printing point and provided with integral

70 lips adjacent to said ribbon holding parts adapted to engage and be guided along the edges of the vertical portion of said upper slot, said ribbon holder having a pendent portion with a substantially T-shaped part extending through the lower slot of said aliner and overlapping the same, and means for operating said holder.

5. In a typewriting machine, the combination of a support, a substantially L-shaped aliner and guide secured to said support and having a vertical slot at the lower portion thereof and a substantially T-shaped slot at the upper portion with integral inturned ends forming a type guide at the upper part thereof, a ribbon holder having substantially C-shaped ribbon holding portions on opposite sides of the printing point and provided with integral lips adjacent to said ribbon holding parts adapted to engage and be guided along the edges of the vertical portion of said upper slot, said ribbon holder having a pendent portion with a projecting substantially T-shaped part extending 80 through the lower slot of said aliner and overlapping the same, and means for operating said holder.

6. In a typewriting machine, the combination of a support, a device having a vertical slot at the lower portion thereof and a slot at the upper portion, a ribbon holder having substantially C-shaped ribbon holding portions on opposite sides of the printing point, and having integral means engaging the edges of both slots for guiding the holder on the device, and means for moving 95 said holder vertically.

7. In a typewriting machine, the combination of a support, an aliner and guide secured to said support and having a vertical slot at the lower portion thereof and a slot at the upper portion and with integral inturned ends forming a type guide at the upper part thereof, a ribbon holder having integral means engaging both slots for guiding the ribbon holder on the aliner, and means for moving said holder.

8. In a typewriting machine, the combination of a support, a carriage adapted to travel along said support, a ribbon holder having substantially C-shaped portions at the upper part thereof with an enlarged body portion substantially V-shaped and provided with a pendent guiding portion, a type aliner and guide forming a support for the ribbon holder and engaged by the pendent guiding portion, and means for operating the ribbon holder.

9. In a typewriting machine, the combination of a support, a carriage adapted to 125 travel along said support, a ribbon holder having guiding portions at the upper part thereof with an enlarged body portion and provided with a pendent guiding portion, a device forming a support for the ribbon 130

holder and engaged by said guiding and pendent portions, and means for operating the ribbon holder.

10. In a typewriting machine, the combination of a support, a carriage adapted to travel along said support, a ribbon holder having guiding portions at the upper part thereof on opposite sides of the printing point, said holder being provided with a pendent guiding portion, a type aliner forming a support and engaged by said guiding portions of the ribbon holder, and means for operating the ribbon holder.

11. In a typewriting machine, the combination of a support having an up-and-down movement, an aliner provided with an index and held to said support, a platen carriage movable along said support and also having an up-and-down movement, a line gage having a substantially V-shaped inverted upper portion and with outwardly extending arms provided with a scale thereon, said line gage being held to said aliner, a ribbon holder interposed between the line gage and the aliner and guided to move vertically on said aliner, and means for moving the ribbon holder.

12. In a typewriting machine, the combination of a support, an aliner provided with an index and held to said support, a platen carriage movable along said support, a line gage having outwardly extending arms provided with a scale thereon, said line gage being held to said aliner, a ribbon holder interposed between the line gage and the aliner and guided to move vertically on said aliner, and means for moving the ribbon holder.

13. In a typewriting machine, the combination of a support, an aliner provided with an index and held to said support, a platen carriage movable along said support, a line gage having a substantially V-shaped inverted upper portion and with outwardly extending arms, said line gage being held to

said aliner, a ribbon holder interposed between the line gage and the aliner and guided to move vertically on said aliner, and means for moving the ribbon holder.

14. In a typewriting machine, the combination of a support having an up-and-down movement, an aliner held to said support, a platen carriage movable along said support and also having an up-and-down movement, a line gage having a substantially V-shaped inverted upper portion and with outwardly extending arms provided with a scale thereon, said line gage being held to said aliner, a ribbon holder interposed between the line gage and the aliner and guided to move vertically on said aliner, and means for moving the ribbon holder.

15. In a typewriting machine, the combination of a support, an aliner held to said support, a platen carriage movable along said support, a line gage having outwardly extending arms provided with a scale thereon, said line gage being held to said aliner, a ribbon holder interposed between the line gage and the aliner and guided to move vertically on said aliner, and means for moving the ribbon holder.

16. In a typewriting machine, the combination of a support, an aliner held to said support, a platen carriage movable along said support, a line gage having a substantially V-shaped inverted upper portion and with outwardly extending arms, said line gage being held to said aliner, a ribbon holder interposed between the line gage and the aliner and guided to move vertically on said aliner, and means for moving the ribbon holder.

This specification signed and witnessed this 14th day of August A. D. 1914.

OTTO PETERMANN.
